Primary Examiner—Ted Shooman*Assistant Examiner*—Mitchell I. Siegel*Attorney, Agent, or Firm*—Cesari and McKenna[57] **CLAIM**

The ornamental design for a children's play tower, as shown.

DESCRIPTION

FIG. 1 is a left front perspective view of a children's play tower showing my new design;

FIG. 2 is a right side elevational view thereof;

FIG. 3 is a front elevational view thereof;

FIG. 4 is a rear elevational view thereof;

FIG. 5 is a left side elevational view thereof;

FIG. 6 is a top plan view thereof; and,

FIG. 7 is a bottom view thereof.

The broken line showing of a slide is for illustrative purposes only and forms no part of the claimed design.
